ELECTRIC-ARC LAMP.

1,007,211.

Specification of Letters Patent. Patented Oct. 31, 1911.

Application filed November 22, 1908. Serial No. 529,446.

To all whom it may concern:

Be it known that I, MAX KÖRTING, a subject of the German Emperor, residing at Leutzsch, near Leipzig, Germany, have invented a new and useful Electric-Arc Lamp, of which the following is a specification.

This invention relates to electric arc lamps supplied with an alternating current and its object is to provide improved means whereby on any lamp being extinguished a compensating impedance shall be switched into the circuit so that the remaining lamps may be unaffected.

Figure 1 of the accompanying drawings shows diagrammatically, one form of lamp made in accordance with this invention while Fig. 2 shows a modified form and Fig. 3 shows another method of carrying out the invention.

1, 2 are the terminals of the main conductor between which is inserted a differential arc lamp the carbons of which are shown at 3, 4.

5 is the winding of the usual series magnet which tends to raise the carbon 3, and 6 that of the usual shunt magnet which tends to lower the carbon 3. Another shunt circuit includes the exciting winding 7 of a switching device and the secondary 8 of a transformer coil, the primary 9 of which acting as a choke coil is inserted in yet another shunt circuit, which can be completed and interrupted by the switch itself shown at 10. The circuit of the choke coil is adapted to cause exactly the same fall of potential as does the lamp when alight.

The diagram shows the parts in the position occupied when the lamp is alight with no current flowing through the choke coil 9 but with a small current, *i. e.* one insufficient to move the switch, flowing through the exciting winding 7 and the secondary 8. Should however the carbon feed become deranged or either of the carbons nearly consumed, then the current in the exciting winding 7 will increase sufficiently to move the switch 10 so that the circuit of the choke coil 9 will be completed, current will flow through this choke coil and the induced current in the secondary 8 flowing through the exciting winding 7 will retain the switch in the required position. It will be seen that this arrangement overcomes the difficulty experienced with this class of apparatus that unless a main current winding is provided

if the compensating resistance is to produce exactly the same fall of potential on the main circuit as does the lamp when alight then when such resistance has been switched into circuit in lieu of a lamp, the current in the exciting winding of the switching device resumes its normal state and the switch is accordingly no longer held.

In the modification shown in Fig. 2 the winding 6 of the shunt magnet of the lamp acts also as the exciting winding of the switching device. As before the winding 5 when excited tends to raise the carbon 3 through its solenoid while the winding 6 when excited tends to lower the carbon 3 through its solenoid. When anything goes wrong with the lamp, more current than is usual in the normal working of the lamp will flow through the winding 6 which becoming highly excited draws down its armature farther than can occur with the normal working of the lamp and causes the switch to close the primary or choke coil circuit.

In place of increasing the voltage of the current in the exciting winding of the switching device by a transformer coil, this may be effected by cutting a resistance out of the circuit of such exciting winding as soon as the compensating resistance has been switched in, this cutting out being accomplished by the movement of the switch itself. This modification is shown in Fig. 3 in which 1, 2 are the terminals of the main conductor between which is inserted a differential arc lamp the carbons of which are shown at 3, 4. 5 is the winding of the usual series magnet which tends to raise the carbon 3 and 6 that of the usual shunt magnet which tends to lower the carbon 3 and also to operate switch contacts 10, 11, 12, 13. 95 9 is a choke coil or ohmic resistance situated in a shunt circuit and adapted to cause when switched in exactly the same fall of potential as does the lamp when alight; one terminal of the coil 9 is connected to the switch terminal 10 and through the other switch terminal 11 to the lamp terminal 2. 8 is a resistance one terminal of which is connected to the switch terminal 12, the resistance 8 being in a circuit which normally includes the winding 6; the other switch terminal 13 is connected to the line leading to the resistance 8. When the lamp is burning normally current flows through the resistance 8 and thence through the winding 6 110

but as explained with reference to Fig. 2 if anything goes wrong with the lamp the winding 6 becomes highly excited and draws down its armature farther than can occur with the normal working of the lamp thus causing the contacts 10, 11, and 12, 13 to close. The circuit of the coil 9 will now be closed and the resistance 8 will be short circuited current passing only through the winding 6 which therefore as in the preceding 10 cases has passing through it a current of higher voltage than when the lamp was alight and the switching device will be held fast when the resistance 9 causes exactly the same fall of potential as does the lamp 15 when alight and this without the employment of a main current winding.

It will be obvious that any form of magnetic switching device comprising an exciting winding may be employed.

What I claim is:—

1. In an alternating current arc lamp, the combination with a main circuit, of a switch having a shunt exciting winding, a transformer having a primary adapted to be switched in said circuit when the switch is operated and adapted to cause practically the same fall of potential in the main circuit as does the lamp when alight, and a secondary of said transformer in series with the said excited winding.

2. In an alternating current arc lamp, the

combination with a main circuit, of a shunt lamp regulating magnet having a shunt exciting winding continuously excited, a switch controlled thereby, a transformer having a primary adapted to be switched in said circuit when the switch is operated and adapted to cause practically the same fall of potential in the main circuit as does the lamp when alight, and a secondary of the transformer in series with the said exciting winding.

3. In an arc lamp, the combination with a set of electrodes and a circuit therefor, of an impedance adapted to replace said electrodes, an electro-magnetic switch for connecting said impedance in circuit, and a winding for said switch connected in shunt to said electrode circuit and having its circuit in inductive relation with respect to said impedance.

4. In an arc lamp, the combination with a set of electrodes and a circuit therefor, of a transformer, an electromagnetic switch adapted to connect the primary of said transformer in said circuit, and a secondary for said transformer in the energizing circuit for said switch.

MAX KÖRTING.
